C. G. HAWLEY

STEEPLED RADIANT HEAT STEAM BOILER

Filed March 15, 1924

UNITED STATES PATENT OFFICE.

CHARLES GILBERT HAWLEY, OF CHICAGO, ILLINOIS.

STEEPLED RADIANT-HEAT STEAM BOILER.

Application filed March 15, 1924. Serial No. 699,594.

This invention relates to steam boilers and their furnaces, and more particularly to that type of boiler in which due regard is given to proper relationship and proportions between the fire and the heat absorbing surfaces provided by the various water-containing elements that make up the boiler or pressure vessel as a whole, to the end that maximum efficiency and capacity may be secured in a steam boiler of minimum size and cost. These results are obtained by the provision of a minor extent of heat absorbing circulating elements so proportioned and disposed as to subdivide and take advantage of the radiant heat of the flames of a long flaming fire and permit such flames without material suppression to rise to substantially full or natural maturity and develop the maximum radiant heat effect; and, by providing in circulating relation therewith major extent of heat absorbing elements so positioned and proportioned as to be capable of economically absorbing or accepting the remainder of valuable heat from the residual gases leaving the fire chamber.

A number of forms of boiler for producing the effects thus briefly described are shown and described in my prior patent for steam boilers, No. 1,486,888 granted March 18, 1924, to which reference may be had for a more complete description and discussion if necessary. For the purposes of this application it is sufficient to say that the results of the invention may be obtained in practically any form or type of boiler, so long as its heat absorbing circulating elements are properly proportioned and positioned with reference to the fire and flames.

The invention consists in the provision in a steam generator of the type comprising a radiant heat section of minor extent and a convected heat section of major extent, situated above the said radiant heat section, of down-comers communicating with headers both of which are arranged vertically, said headers communicating with up-comers forming the radiant heat section of the generator.

The present application has particular relation to a boiler of steeped form, in which the heat absorbing circulating tubes of major extent for absorbing the convected heat are superposed upon or lie above the combustion chamber in which the radiant heat is most efficiently developed and transmitted to the heat absorbing circulating elements of

minor extent which occupy that chamber. This boiler may also, at least partly be constructed in sectional form, with improved header members of simple and efficient form and of a size convenient for transportation and erection purposes. The boiler also is well adapted for efficient firing and does away with any necessity of large heavy drums such as are usually necessary on high pressure steam boilers, and on the contrary may embody relatively small drums and other heat absorbing elements and still develop the necessary high pressure to meet the modern trend of boiler practice. The arrangement of the heat absorbing circulating tubes is convenient for erection, renewal and repair purposes, for insertion, removal or repair of arches or baffle walls; and, also provides the necessary available space for super-heater elements, where such are used. In addition, the various elements of the boiler are so disposed and arranged as to provide for rapid separation of steam with violent coursing of the water over the surfaces with which it contacts to fully protect the same, all within a minimum of space and with maximum steaming capacity for the available surface area, number and weight of tubes and other boiler elements utilized.

In the drawings, Fig. 1 represents a longitudinal sectional elevation on the line 1—1 of Fig. 2, through one form of boiler embodying the invention; Fig. 2 is a partial transverse sectional elevation on the irregular line 2—2 of Fig. 1; and Figs. 3 and 4 are longitudinal vertical sections of two modified forms of the boiler.

The boiler of Figs. 1 and 2 is most conveniently designed and proportioned to occupy two stories and the basement, (not shown) of a boiler house. It will be understood that the structural members of the building may conveniently be employed for the support of the heavier upper part (the convected heat absorbing portion) of the boiler. The radiant heat absorbing portion of the boiler is suspended from the convected heat absorbing parts thereof.

The main floor line is marked 2 and the floor of the second story is marked 3; the latter structure includes the heavy cross girders, 4, on which the convected heat portion of the boiler is erected. That portion, in the instant case, is made up of three units, 5, each comprising a large bank of tubes, 6, and two headers, 7 and 8, to which the tubes

are connected. The headers are preferably of the advantageous form which is described and claimed in my companion application S. N. 698,213. These headers extend both 5 above and below the bank of tubes, 6, and receive, in each case, a small drum, 9, at the bottom and a large drum, 10, at the top. The drum 9, is accessible through manholes, 9'; likewise drums 10, through manholes 10'. 10 The headers are suitably stay bolted and are parallel. All of the parts 6, 9 and 10, are properly perpendicular to the headers. Any suitable means may be used for fastening the plurality of units together mechanically. 15 They are also in free intercommunication, as concerns the circulation of water and steam, such intercommunication being established through the medium of the suspended wall forming cross headers, 11 and 20 12, the down tubes, 13 and 14, and the riser tubes, 15 and 16; all about to be described. For the purposes of positively directing the circulatory flow of water and steam within the boiler, the convected heat absorbing sections are inclined at about five degrees to 25 the horizontal, or more if desired; this is merely a matter of the relative positions of the supporting frame work 4. A steam desaturator drum 17, is connected with the 30 headers 8, by many tubes, 18; 19 is the outlet nozzle of the boiler; and 20 represents the smoke stack. Generally the superheater 21, is accommodated in the space 22 provided therefor directly above the drums 9 35 and below the tubes 6. The superheater is diagrammatically shown in Fig. 2 and is assumed to be connected with the outlet 19. The extensiveness of the superheater is represented by the dotted rectangle 21' in Fig. 1. 40 The tubes 13 and 14 of the front and back rows are many in number and are the tubes through which the water returns, i. e., flows downward to the headers 11 and 12, respectively. Incidentally, the front and back 45 furnace walls 23, brick, are interfitted with these tubes, which hold them in place; the weight of the walls being supported by the headers 11 and 12. The walls 23 extend upward and tightly join the lower ends of respective vertical headers 7 and 8, which latter in themselves complete the upper portions of the front and back walls of the boiler. The side walls 25 are usually composed of brick and extend to the top of the 50 boiler, where, in company with the headers 7 and 8, they support the stack base 20. 55 The bent tubes, 15 and 16, extend from respective headers, 11 and 12 and rise into communication with the drums, 9. In one direction these tubes are quite closely spaced, but in a transverse direction they are widely spaced to present the wide flame spaces, 26, well shown in Fig. 2. These are the chief 60 radiant heat absorbing elements of the boiler. 65 The flame dividing and heat absorbing func-

tions of these partition-like arrangements of tubes 15 and 16 will now have become familiar through the explanations of aforesaid companion application S. N. 643,731, Patent Number 1,486,888. They occupy the tall 70 combustion chamber *a*, within the four walls 24 and 25 and the front and back walls containing the imbedded pipes 13 and 14, but are so few in number and so widely spaced as not to interfere with the free and natural 75 complete combustion of the gases in the fire chamber *a*, at least to any material degree. In the instant case, the fire or combustion chamber *a*, is assumed to be employed in the combustion of pulverized coal, gas or oil 80 by any well known means. Obviously the lower part of the combustion chamber, *a*, may contain either hand fired grates or automatic stokers of any desired type.

To avoid over-weighting the dependent 85 cross-headers, 11 and 12, and for reasons of convenience and low cost, the walls 13 and 14 are made comparatively thin. They are made leak proof by metal jackets that are attached to the supporting parts. To avoid 90 loss of heat the front and back walls, 13 and 14, and associated headers, are concealed behind metal screens, 13' and 14'. These screens extend from the base of the convected 95 heat absorbing sections, 5, to the floor 2. They are spaced away from respective walls, 100 providing the air channels 26. At the bottom the spaces 26 communicate with openings 27, through which the heated air is 105 drawn into the combustion chamber and there advantageously used. An air jacket, 26', may also be provided for the open side wall, 24, enabling a thin wall to be used. The wall 25, is assumed to be a mid-wall 110 between two boilers of a battery.

The arrows of Fig. 1 so fully indicate the simple and effective flow of the boiler contents that it seems unnecessary to describe the same in detail. In practice the boiler is fully equipped with the usual accessories 115 common to steam boilers. Generally the boiler of Figs. 1 and 2 comprises a simple single pass boiler; that is it does not require internal baffles other than a few lines of brick, 28, to prevent too direct upward 120 flow of the gases between the wider spaces necessarily existing between the several banks of tubes 6. However, it will be obvious that whether or not baffles are employed depends somewhat upon the number 125 and area of the tubes 6. Where they are fewer in number it is an easy matter to arrange baffles at several points in the form of horizontal floors resting upon the lower drums 9' and the tubes 6' as shown in Fig. 3. Fig. 3 also exhibits a convected heat section of a modified form, in which the upper 130 steam drums are dispensed with. In such cases the boiler is worked with a water line 29, which leaves the uppermost tubes free. 135

Those tubes amply provide for a nice disengagement and for the preliminary drying or superheating of the steam.

Fig. 4 represents a modified form of this invention differing from the others in these important respects. At the front the boiler has a plurality of upright headers 8', each receiving a large group of tubes, 30. The tubes from all of the headers 8' are joined to a single cross header, 31. From the latter a plurality of down tubes, 32 supply a smaller cross header, 33. The inclined drum 34, is closed at its lower end 35, and extends outward through the wall 32', which latter 10 resembles the walls wherein the pipes 13 and 14 are imbedded as before described. The upper end of the drum, in each case communicates, or opens into the lower end of its respective upright header, 8'. There may 15 be one or several of the drums, 34 for each header 8', depending upon the size of the parts; and always bearing in mind that the several drums 34 must be spaced apart in order that the gases may pass between them 20 and reach the space that contains the tubes 30. For each drum 34 I provide a substantially triangular waterleg, 36, which in itself resembles the well known Nicholson thermic siphon. The top of the waterleg, 30 25 36, opens directly into the bottom of the drum 34; the neck, 36' of the leg, is connected to the cross header 33, and draws water therefrom. Obviously the several walls or siphons, 36, are separated by wide flame 30 35 passages and that in this particular the suppression of combustion in the chamber 37 is obviated. It should be noted that the several parts of this boiler are so flexibly connected as to avoid any detrimental effects 40 from expansion and contraction. The boiler of Fig. 4 will be found to be of great advantage where boilers of low cost, high capacity and small size are required.

Various modifications of this invention 45 will readily suggest themselves to one who is skilled in the art, and therefore it is to be understood that the invention is not restricted to the specific structures herein disclosed.

Having thus described my invention I 50 claim as new and desire to secure by Letters Patent:—

1. A casing or setting containing a tall combustion chamber admitting of the substantially natural maturity therein of the flame of a body of long flaming fire, in combination with a steam boiler comprising a radiant heat absorbing portion in said chamber and a convected heat absorbing portion 55 positioned above said chamber to receive the hot gases therefrom, said radiant heat absorbing portion including opposed parallel header members near the bottom of said chamber, parallel horizontally extending intermediate drums in the upper portion of

said chamber and a minor extent of heat absorbing circulating tubes rising from said header members to said drums and widely spaced in and across said chamber, and said convected heat absorbing portion including 70 upright wall forming header members connected to the ends of said intermediate drums, a major extent of substantially horizontally extending heat absorbing circulating tubes connecting said upright header 75 members, and a superheater member located above said intermediate drums and below said horizontally extending circulating tubes.

2. A casing or setting containing a tall 80 combustion chamber admitting of the substantially natural maturity therein of the flame of a body of long flaming fire, in combination with a steam boiler comprising a radiant heat absorbing portion and a convected heat absorbing portion positioned 85 above said chamber to receive the hot gases therefrom, said radiant heat absorbing portion including opposed horizontal headers near the bottom of said chamber together 90 with intermediate drums in the upper portion of said chamber and a minor extent of heat absorbing circulating tubes rising from said header members to said drums and widely spaced in and across said chamber 95 and said convected heat absorbing portion including parallel upper drums together with upright wall forming headers connecting the ends of said upper and intermediate drums and a major extent of heat absorbing 100 circulating tubes connecting said upright headers, and, a superheater member located above said intermediate drums and below said horizontally extending circulating tubes.

3. A casing or setting containing a tall combustion chamber admitting of the substantially natural maturity therein of the flame of a body of long flaming fire, in combination with a steam boiler, including a 110 radiant heat absorbing portion and a convected heat absorbing portion positioned above said chamber to receive the hot gases therefrom, said radiant heat absorbing portion including opposed parallel header members near the bottom of said chamber, parallel horizontally extending intermediate drums in the upper portion of said chamber, and a minor extent of heat absorbing circulating tubes connecting said header members and drums and extending into the flame in said chamber to thereby increase its radiant area and permit it to rise to substantially natural maturity in said chamber, and said convected heat absorbing portion including 115 upright wall forming header members connected to the ends of said intermediate drums, a major extent of substantially horizontally extending heat absorbing circulating tubes connecting said upright header 120 125 members.

members, return tubes connecting said upright header members and said opposed header members, and a superheater member located above said intermediate drums and below said horizontally extending circulating tubes.

4. A casing or setting containing a tall combustion chamber admitting of the substantially natural maturity therein of the flame of a body of long flaming fire, in combination with a steam boiler, including a radiant heat absorbing portion and a convected heat absorbing portion positioned above said chamber to receive the hot gases therefrom, said radiant heat absorbing portion including opposed parallel header members near the bottom of said chamber parallel horizontally extending intermediate drums in the upper portion of said chamber, and a minor extent of heat absorbing circulating tubes connecting said header members and drums and extending into the flame in said chamber to thereby increase its radiant area and permit it to rise to substantially natural maturity in said chamber, and said convected heat absorbing portion including parallel, horizontally extending upper drums, upright wall forming header members connecting the ends of said upper and intermediate drums, a major extent of substantially horizontally extending heat absorbing circulating tubes connecting said upright header members, return tubes connecting said upright header members and said opposed header members, and a superheater member located above said intermediate drums and below said horizontally extending circulating tubes.

5. A casing or setting containing a tall combustion chamber admitting of the substantially natural maturity therein of the flame of a body of long flaming fire, in combination with a steam boiler comprising a radiant heat absorbing portion in said chamber and a convected heat absorbing portion positioned above said chamber to receive the hot gases therefrom, said radiant heat absorbing portion including headers near the bottom of said chamber, together with parallel intermediate drums in the upper portion of said chamber and a minor extent of radiant heat absorbing circulating tubes connecting said headers and drums and widely spaced in and across said chamber, and said convected heat absorbing portion including upright wall forming headers rising from the ends of said intermediate drums together with a major extent of convected heat absorbing circulating tubes joining said upright headers, and a superheater member extending transversely of the last mentioned tubes and positioned between the lowermost thereof and said intermediate drums.

6. A casing or setting containing a tall combustion chamber admitting of the sub-

stantially natural maturity therein of the flame of a body of long flaming fire, in combination with a steam boiler comprising a radiant heat absorbing portion in said chamber and a convected heat absorbing portion positioned above said chamber, said radiant heat absorbing portion including opposed horizontal headers near the bottom of said chamber together with parallel intermediate drums in the upper portion of said chamber, and a minor extent of heat absorbing circulating tubes connecting said headers to said drums and extending within said chamber and said convected heat absorbing portion including upper drums together with upright wall forming headers connecting the ends of said upper and intermediate drums, and a major extent of convected heat absorbing circulating tubes joining said upright header members, and a superheater member positioned transversely between last mentioned tubes and said intermediate drums.

7. A casing or setting containing a tall combustion chamber admitting of the substantially natural maturity therein of the flame of a body of long flaming fire, in combination with a steam boiler, including a radiant heat absorbing portion and a convected heat absorbing portion positioned above said chamber to receive the hot gases therefrom, said radiant heat absorbing portion including opposed parallel header members near the bottom of said chamber, parallel horizontally extending intermediate drums in the upper portion of said chamber, and a minor extent of heat absorbing circulating tubes connecting said header members and drums and extending into the flame in said chamber to thereby increase its radiant area and permit it to rise to substantially natural maturity in said chamber and said convected heat absorbing portion including upright wall forming header members connected to the ends of said intermediate drums, a major extent of substantially horizontally extending heat absorbing circulating tubes connecting said upright header members, return tubes connecting said upright header members and said opposed header members, and a superheater member extending transversely of the horizontally extending circulating tubes and positioned between the same and said horizontally extending intermediate drums.

8. A casing or setting containing a tall combustion chamber admitting of the substantially natural maturity therein of the flame of a body of long flaming fire, in combination with a steam boiler, including a radiant heat absorbing portion and a convected heat absorbing portion positioned above said chamber to receive the hot gases therefrom, said radiant heat absorbing portion including opposed parallel header members near the bottom of said chamber, parallel hori-

- zontally extending intermediate drums in the upper portion of said chamber, and a minor extent of heat absorbing circulating tubes connecting said header members and 5 drums and extending into the flame in said chamber to thereby increase its radiant area and permit it to rise to substantially natural maturity in said chamber, and said convected heat absorbing portion including 10 parallel, horizontally extending upper drums, upright wall forming header members connecting the ends of said upper and intermediate drums, a major extent of substantially horizontally extending heat absorbing 15 circulating tubes connecting said upright header members, return tubes connecting said upright header members and said opposed header members, and a superheater member extending transversely of the 20 horizontally extending circulating tubes and positioned between the same and said horizontally extending intermediate drums.
9. A steam generator of the type claimed in claim 2, having the superheater situated 25 transversely to the circulating tubes in the convected heat section.
10. A steam generator comprising a casing or setting containing a tall combustion chamber admitting of the substantially natural 30 maturity therein of the flame of a body of long flaming fire, in combination with a steam boiler, comprising a radiant heat absorbing portion in said chamber and a convected heat absorbing portion positioned 35 above said chamber to receive the hot gases therefrom, said radiant heat absorbing portion including opposed parallel header members near the bottom of said chamber together with bottom forming parallel 40 horizontally extending intermediate drums in the upper portion of said chamber, and a minor extent of heat absorbing riser elements widely spaced within said chamber and connecting said header members and 45 drums, and said convected heat absorbing portion including upright wall forming

header members in communication with the ends of said intermediate drums, together with a major extent of substantially horizontally extending heat absorbing circulating 50 tubes extending between said upright header members, the main axis of the generator being inclined to the perpendicular, the tubes forming the riser elements being arranged parallel to the main axis, and the 55 tubes in the convected heat section lying in a plane or planes at right angles thereto.

11. A steam generator comprising a casing or setting containing a tall combustion chamber admitting of the substantially natural 60 maturity therein of the flame of a body of long flaming fire, in combination with a steam boiler, including a radiant heat absorbing portion and a convected heat absorbing portion positioned above said chamber 65 to receive the hot gases therefrom, said radiant heat absorbing portion including opposed parallel header members near the bottom of said chamber, parallel horizontally extending intermediate drums in the 70 upper portion of said chamber, and a minor extent of heat absorbing circulating tubes connecting said header members and drums and extending into the flame in said chamber to thereby increase its radiant area and permit it to rise to substantially natural maturity in said chamber, and said convected heat absorbing portion including parallel, horizontally extending upper drums, upright 75 wall forming header members connecting the ends of said upper and intermediate drums, a major extent of substantially horizontally extending heat absorbing circulating tubes connecting said upright header members, and return tubes connecting said 80 upright and horizontally extending header members, in combination with a superheater member located above said intermediate drums and below said circulating tubes.

In testimony whereof I hereto affix my 90 signature.

CHARLES GILBERT HAWLEY.
